UNITED STATES PATENT OFFICE.

FRED EBERLEIN, OF CHICAGO, ILLINOIS.

DESIGN FOR A SHOW-CARD.

SPECIFICATION forming part of Design No. 16,246, dated September 15, 1885.
Application filed October 13, 1884. Term of patent 7½ years.

To all whom it may concern:

Be it known that I, FRED EBERLEIN, of Chicago, in the county of Cook and State of Illinois, have invented a certain new and original Design for Show-Cards; and I do hereby declare the following to be a full, clear, and exact description of the same, reference being had to the accompanying drawing, in which is represented a perspective view of my design.

My design relates to show-cards; and it consists in the peculiar outline form of the card or backing, and in the corresponding general form of the work placed upon its face, where-
15 by the effect is heightened and rendered more complete.

a represents the main body of my card, which consists simply of a flat card having the central portion of its upper edge made horizontal, as at *a'*, and the upper corners cut away to form inclines *a''*, as fully seen in the drawing.

On the face of the card are shown the receptacles *b*, and these are shaped as shown in the configuration, being exactly parallel with the plain and angular upper edge of the card.

Having thus fully described my invention, what I desire to secure by Letters Patent is—

The design for show-cards herein shown and described, consisting of a card having its upper edge formed with a central straight portion and its upper corners beveled at an incline, the receptacles *b* being shown on the face of the card, and shaped as shown, the configuration being exactly parallel with the plain and angular upper edge of the card, substantially as shown and described.

FRED EBERLEIN.
